UNITED STATES PATENT OFFICE.

CLARENCE E. REED, OF HOUSTON, TEXAS.

WRENCH.

1,412,260.

Specification of Letters Patent. Patented Apr. 11, 1922.

Application filed July 29, 1920. Serial No. 399,782.

To all whom it may concern:

Be it known that I, CLARENCE E. REED, a citizen of the United States, and resident of Houston, Texas, have invented certain new and useful Improvements in Wrenches, of which the following is a specification.

The invention relates to pipe wrenches and while particularly designed to do heavy work, such as in connection with the drill stems of deep well drilling apparatus, it will be understood that the wrench is susceptible of being built of such a size and form as to adapt it to lighter work.

The invention consists in the features and combination and arrangement of parts hereinafter described and particularly pointed out in the appended claims.

In the drawings; Figure 1 is a view of the pipe wrench with the head portion thereof partly in section.

Figure 2 is a sectional view taken lengthwise of the wrench and at a quarter turn from Figure 1.

Figure 3 is a perspective view of one of the gripping dogs belonging to the head of the wrench.

In these drawings 1 indicates the head in the form of a yoke having the two jaws 2, 2. This head in the present embodiment 30 of the invention is shown as formed of one piece with its jaws integral with each other.

The head is provided with a groove 3 in its face, the inner margins of this groove having overhanging flanges indicated at 4.

35 Within this groove blocks 5 are fixed, these being in the form of wedges and they are retained in place by pins 6. The wedge blocks serve to guide gripper devices 7 which are provided, each with an inclined face 8 and gripping point 9. These grippers bear one upon another throughout the series and there is a series of these devices arranged in each jaw. They are held from dropping out by pins 9' taking under the overhanging flanges.

45 A master wedge 10 is arranged centrally of the head of the wrench and this master wedge bears upon the first gripper device or gripper dog of each series, so that when this 50 master wedge is thrust forwardly it will impart a movement to each series of gripping devices and cause the members of each series to slide up the incline of its guiding wedge block 5 and thus project the gripping point

or tooth 9 so as to grip the pipe for turning 55 the same.

The movement imparted by the master wedge to the first gripping device or dog is transmitted to the second gripping device and so on throughout the series. 60

The master wedge is operated by the head portion 11 of a handle 12 which is pivoted to the head or yoke by a pin 13 passing through the flanges, or ears 14 of the head of the wrench. 65

The head portion of the pivoted handle is provided with a pin 15 working in a slot in the flanges 14 of the head by which the relative movement of the handle in respect to the head of the wrench is limited. 70

It will be observed that by exerting pressure upon the handle in the proper direction the master wedge will be advanced and thus set the gripping devices in position to firmly grip the pipe to be turned. 75

The wrench may be used either left-hand or right-hand, its position when used as a left-hand wrench being reversed from its position when used as a right-hand wrench. 80

It will also be seen that the handle is arranged centrally in respect to the head and its pivot lies to one side of the general lengthwise axis of the wrench. The plain upper end of the handle has a cam action on the stem of the master wedge, which stem projects into the space between the ears 14 of the wrench head. 85

The master wedge is guided in a recess formed at the junction of the two jaws of the wrench. 90

In the use of the appliance the head thereof is set so as to embrace the pipe and then by swinging the handle in the direction necessary to turn the pipe or other object, the first effect will be to operate the master wedge by the pressure exerted from the head of the handle, and the series of wedge-shaped gripper dogs thus will be set against the pipe and further movement of the handle in the same direction will result in turning the pipe. 95

While I have shown one form of wrench embodying the invention, I desire it understood that this is illustrative of the general principles involved and is not to be regarded as restrictive upon the scope of the novelty of the invention, this being defined by the appended claims. 100

I claim:

1. A wrench comprising a jaw, gripping devices carried thereby and individually movable substantially radially of the jaw, an opposing jaw, a master member for operating the gripping means, and a handle for turning the wrench, said handle also effecting the operation of the master member to set the gripping means into engagement with the object, substantially as described.

2. A wrench comprising a jaw, gripping devices carried thereby and individually movable substantially radially of the jaw, an opposing jaw, a master member for operating the gripping means, and a handle for turning the wrench, and by the same movement performed for turning the wrench, effecting the operation of the master member to set the gripping means into engagement with the object, substantially as described.

3. A wrench comprising a jaw, grips carried thereby movably, a series of fixed inclines along which the grips move to be thereby projected inwardly to engage the object, a master member and means for operating the master member for operating the grips, said grips bearing one upon another whereby the movement of the master member is transmitted from one grip to the next adjacent grip, substantially as described.

4. In combination in a wrench, a jaw having a channeled face with overhanging flanges, a series of grips with portions engaging under said flanges and held against loss thereby, a series of fixed inclines in the channel and upon which the grips work to be projected inwardly to engage the object, an opposing jaw, a master wedge and means for operating the master wedge to set the series of grips against the object, substantially as described.

5. In combination in a wrench, a jaw with gripping means movably mounted thereon, an opposing jaw, a master member slidable radially of the jaw for operating the gripping means, a handle pivotally mounted and controlling by its pivotal movement the operation of the master member, said handle being the means for turning the wrench, substantially as described.

6. In combination in a wrench a head having a jaw with gripping means movably mounted thereon, an opposing jaw, a master member guided in the head for operating the gripping means, a handle pivotally connected with the head and having a portion in engagement with a part of the master member, said handle serving to operate the master member when pressure is applied to said handle to turn the wrench, substantially as described.

7. In combination in a wrench, a jaw, gripping means mounted thereon, an opposing jaw, a master member for operating the

gripping means, and a handle pivoted to one side of the point where the jaws join each other and having a portion extending laterally from the pivot to engage and operate the master member when the handle is pressed upon and swung for turning the wrench, substantially as described.

8. In combination in a wrench, a head having a jaw, gripping means mounted on the jaw, an opposing jaw, rigid with the jaw first mentioned, a master member on the head, a handle pivoted on the head and having a portion for operating the master member, in the same movement thereof which is performed for operating the wrench.

9. In combination in a wrench, a head, a pair of rigid jaws in the head, gripper means movable in relation to the jaws, a master wedge member arranged at the junction of the jaws, a handle extending with its center coinciding with the center line between the jaws, and with the line of movement of the master wedge member, said handle being pivotally mounted at a point to one side of the said center line and having a portion engaging a part of the master wedge member, substantially as described.

10. A wrench comprising a head having a pair of rigid jaws, gripping means, a master member arranged at the junction of the jaws for operating the gripping means, a socket in which said master member operates, a stem on said master member, and a handle pivoted to one side of the center line passing between the jaws and having a portion to bear on said stem for operating the master member, substantially as described.

11. A wrench comprising a head having a pair of jaws, and having gripping means and a master member for operating them, a handle pivoted to the head for operating the master member in the same movement which is given the handle to turn the wrench, and means for limiting the movement of the handle relative to the head, substantially as described.

12. A wrench comprising a head having a pair of jaws, and having gripping means and a master member for operating them, a handle pivoted to the head for operating the master member in the same movement which is given the handle to turn the wrench, and means for limiting the movement of the handle relative to the head, said means consisting of a pin and slot connection between the handle and the head of the wrench, substantially as described.

13. A wrench having a head with a pair of rigid jaws and with ears extending from the back of the head and centrally thereof, gripping means movably carried by the jaws, a master wedge arranged at the junction of the jaws, and movable towards and from the center of the space between the jaws, a recess in the head at the junction of

- the jaws in which the master wedge is guided, a stem on the wedge member projecting into the space between the ears, a handle extending in a general direction in line with the center of the jaws, and pivoted between the ears off to one side of said center line, and having a portion extending to one side of its pivot for operating the wedge, substantially as described.
- 10 14. A wrench having a head with a pair of rigid jaws and with ears extending from the back of the head and centrally thereof, gripping means movably carried by the jaws, a master wedge arranged at the junction of the jaws, and movable towards and from the center of the space between the jaws, a recess in the head at the junction of the jaws in which the master wedge is guided, a stem on the wedge member projecting into the space between the ears, a handle extending in the general direction in line with the center of the jaws, and pivoted between the ears off to one side of said center line, and having a portion extending to one side of its pivot for operating the wedge, substantially as described.
- 15 15. In combination in a wrench, a head having a jaw with gripping means movably mounted thereon, a master member on the head for operating the gripping means, a handle pivoted to the head and operating the said master member when the handle is moved to turn the wrench, said wrench being reversible for operating right-hand or left-hand, substantially as described.
- 20 16. In combination in a wrench, a head having rigid jaws, gripping means movably mounted in each jaw, a master wedge at the center of the jaws, and a pivoted handle, the operation of which operates the master wedge to operate the grips and by the movement of the handle in the direction for turning the wrench with the object gripped thereby.
- 25 In testimony whereof, I affix my signature.

CLARENCE E. REED.
